CLAIM

The ornamental design for a bag clip for bringing the edges of thick, inflexible bags together, as shown and described.

DESCRIPTION

FIG. 1 is a top, front and left-side perspective view of a bag clip for bringing the edges of thick, inflexible bags together showing my new design;

FIG. 2 is a front elevational view thereof;

FIG. 3 is a rear elevational view thereof;

FIG. 4 is a top plan view thereof, a bottom plan view being identical thereof;

FIG. 5 is a right-side elevational view thereof;

FIG. 6 is a left-side elevational view thereof;

FIG. 7 is a bottom, rear and right-side perspective view thereof;

FIG. 8 is an alternate bottom, front and right-side perspective view thereof showing the bag clip in use;

FIG. 9 is an alternate front elevational view thereof showing the bag clip in use;

FIG. 10 is an alternate front elevational view thereof showing the bag clip in use; and,

FIG. 11 is an alternate front elevational view thereof showing the bag clip in use.

The broken lines depict environment that forms no part of the claimed design.
